WIRE TWISTING MACHINE

Gunnar L. Whist, Oslo, Norway

Application March 21, 1938, Serial No. 197,114
In Germany March 25, 1937

9 Claims. (Cl. 153—78)

The present invention relates in general to a machine for twisting wire and more particularly to a machine for twisting a substantially endless wire, having an angular cross section, about its axis in order to obtain a helically twisted wire adapted especially for use in the manufacture of drive screw nails or the like.

Machines of this type have prior to my invention been rather limited in their wire twisting capacities because of the arrangement therein of essential parts such as the position and movement of the revolving frame or spider relative to the untwisted wire supply drum and the twisted wire receiving drum.

My invention is an improvement upon these prior machines and more especially an improvement upon the type of wire twisting machine covered by K. J. Jensen Patent 1,998,582.

Although an embodiment of my invention may include the valuable principle covered by said Jansen patent, i., e., the bending of the wire partially about a roller at an acute angle to its previous direction of travel, to obtain a more uniform helical twist or pitch, it is to be understood that my invention is not limited by the incorporation of the Jensen principle but is independent thereof.

An object of my invention is the provision of a wire twisting organized apparatus whereby and wherein the output of twisted wire is increased while the speed of the revolving twisting frame is decreased and the centrifugal action on said frame and the parts revolving therewith is also correspondingly decreased.

Another object of my invention is the provision of such a wire twisting machine whereby and wherein the bodily revolution of the untwisted wire supply and twisted wire receiving drums with the revolving wire twisting frame is entirely eliminated.

Another object of my invention is the provision of such a machine whereby and wherein the output is doubled without duplicating certain essential and expensive parts such as the revolving wire twisting frame, thereby effecting a considerable saving in the cost of the machine and in floor space in the factory.

Still another object of the invention is the provision of a novel machine wherein the wire, though fed in opposite direction, receives cooperating axial twists in the same direction to produce a finally desired helically twisted wire of predetermined pitch.

Numerous other objects and advantages of the invention will be apparent as it is better under-

stood from the following description, which, taken in connection with the accompanying drawings, discloses a preferred embodiment thereof.

5 Referring to the drawing:

Figure 1 is a side elevation of a preferred form of apparatus embodying my invention with parts in section and broken away.

Fig. 2 is an enlarged fragmentary top plan view taken along the line 2—2 of Fig. 1 and showing wire fed from the upper unwinding or wire supply drum to the gripping roller and bending rollers where the first axial half twist of the wire takes place.

Fig. 3 is an enlarged fragmentary top plan view taken along lines 3—3 of Fig. 1 and showing the partially twisted wire wound once around the gripping roller and fed to the bending rollers where the second axial half twist completes the twisting of the wire.

The machine comprises generally a revolving loop or ring-like wire twisting frame A, a stationary substantially U-shaped wire supply drum supporting frame B suspended within the frame A, untwisted wire supply drums C and D and twisted wire receiving drums E and F, and a power connecting drive gear G. These parts are generally supported by a number of standards resting on or being secured to a floor or base H, which is recessed at I to give clearance to revolving parts of the machine and to reduce its overall height.

The frame A comprises an oblong main frame ring or loop 11 and two side ring or loop frame extensions 12 and 13. The rings 11, 12 and 13 have aligned bores along their longitudinal axes which provide bearings for hollow shafts 14, 15, 16 and 17. The bearings provided by frame extensions 12 and 13 are keyed to the inner ends of the hollow shafts 14 and 17 respectively. The bearings provided by main frame 11 are keyed to the outer ends of the hollow shafts 15 and 16 respectively, so that the main frame 11 together with frame extensions 12 and 13 revolves with the hollow shafts 14, 15, 16 and 17 in unison.

The shafts 14 and 17 are revolvably mounted in bearings provided by standards 18 and 19 respectively and are provided at their outer ends with annular stop flanges 21, which are integral with forked gripping roll bearing brackets 22. Driving gears 23 and 24 are keyed to the shafts 14 and 17 respectively between the stop flanges 21 and the bearings of standards 18 and 19 respectively.

The hollow shafts 15 and 16 terminate at their

inner ends in annular stop flanges 25, which are integral with horizontal shelves or brackets 26, upon which are mounted a series of rollers preferably in the arrangement shown in Fig. 2.

The main frame 11 has secured to it upon its outer periphery forked brackets in which are mounted wire guiding idler rollers 27, having curved annular wire receiving grooves or recesses. Similar cooperating wire guiding idler rollers 28 are mounted in forked brackets secured to the inner periphery of the frame extensions 12 and 13.

Upon the inner ends of the hollow shafts 15 and 16 are loosely mounted the bearing ends or legs of the substantially U-shaped frame B, which thus becomes non-rotatably suspended within frame A by its own gravity and the weight of its attachments. Centrally of this frame is fixedly mounted a vertical shaft or spindle 29 which provides a bearing of large diameter for the lower drum D having a wire coil supporting and stop flange 31 and a bearing of smaller diameter for the upper drum C having a wire coil supporting and stop flange 32. This arrangement permits the positioning of the filled and removal of the empty drums or reels C and D. The stationary frame B also has fixedly secured to the inner periphery of its opposed legs, rigid elbow brackets 33 each having preferably a pivoted top member upon which is mounted adjacent the brackets 26, a gripping roller 34, having an annular wire receiving groove or recess of a cross sectional shape and dimension to exactly fit the cross section of the wire, which may be square, rectangular, triangular or any other suitable angular shape, so that the wire when being fed over this roller 34 is held against axial rotation but is permitted to be fed onward.

Upon the outer side of standard 18 and the outer side of standard 19 are secured supporting brackets 35 and 36 respectively. Both are identical in construction and purpose and each is formed with a horizontal shelf 37 (Fig. 3) upon which are mounted a series of rollers, preferably four in number. One of these rollers, in accordance with the teachings of the Jensen patent above mentioned, may be used as a wire bending and gripping roller, i. e., to impart an acute angle bend to the wire or direct the travel of the wire at an acute angle relative to its previous direction of travel. The roller which performs this function is designated by reference numeral 38 (Fig. 3). Cooperating with bending and gripping roller 38 is gripping roller 39 mounted in the forked bracket 22. It is between the gripping roller 39 and the bending and gripping roller 38 that the second half twist of the wire is performed, the first half twist having already taken place between gripping roller 34 and bending and gripping roller 38.

Comparing now the gripping and bending rollers in Fig. 3 with those in Fig. 2, it will be noted that the effective wire twisting distance between the bending and gripping roller 38 and gripping roller 39 is the same as the effective wire twisting distance between gripping roller 34 and bending and gripping roller 38', the wire being twisted while also being bent at an acute angle in each case.

The cross section of the annular grooves of rollers 38 and 38' may also be identical, preferably curved. The cross section of the annular recesses of rollers 39 and 34 are not identical, however; the latter roller's function being to grip against axial rotation an untwisted wire, usually of square cross section, and the roller 39 having

5 to grip a wire which has already received a half twist. I have found that a simple means of preventing the half twisted wire from turning axially before it reaches the proper twisting zone is to wrap it once around the recessed roller 39 of a diameter large enough to prevent binding of the wire upon the roller against onward travel, but other suitable gripping means may be employed.

The machine is driven in a synchronized manner by connecting the drive gear G, mounted on drive shaft 41, with any suitable source of power (not shown). The drive shaft 41 has bearings in standard 18 and standard 42. Rotation of the shaft 41 imparts rotation to gear 43, which meshes 10 with gear 23, and thereby to the frame 11 and frame extensions 12 and 13 and all the parts connected therewith, including gear 24 on the right hand side of the frame A. Gear 24 is in mesh with gear 44 mounted on shaft 45, which 15 has bearings in standard 19 and standard 46. The twisted wire receiving drum E secured to vertical shaft 47 is rotated through bevel gear 48 in mesh with bevel pinion 49 secured to the end of drive shaft 41. In like manner twisted wire receiving drum F on the right hand end of the machine and secured to vertical shaft 51 is rotated through bevel gears 52-53.

30 The preferred practice of the method may be outlined by a brief description of the operation of the exemplified machine. Fig. 1 shows in dotted lines a supply of wire 54 coiled upon the reels or drums C and D, revolutely mounted upon the vertical spindle 29.

35 Following the travel of one of the wires 54 from the wire supply drum C, as an example, the wire is fed over gripping roller 34 which holds it against axial rotation but permits its onward travel over bending roller 38' (Fig. 2) which is so positioned relative to said gripping roller 34 and 40 the remaining rollers upon shelf 26 that the wire 54 is given an acute angle bend relative to the direction of travel of the wire between rollers 34 and 38'. The wire is thus given its first twist between the gripping roller 34, on stationary bracket 33 and the wire bending roller 38' on revolving bracket 26. This twist imparts one-half the ultimately desired pitch per linear unit measure. I have also discovered that the effective wire twisting distance between the rollers 34 and 38' on the one hand and between the rollers 39 and 38 on the other hand should be comparatively short to insure proper twisting control and best twisting results. The wire then travels in a preferably straight line through the remaining rollers 45 on bracket 26, thence through hollow shaft 16, 50 thence over the upper idler guide roller 28 within the frame extension 13, through an oblique perforation in the frame extension 13, thence over two of the idler guide rollers 27, through an oblique 55 perforation of the frame extension 12, over the upper guiding roller 28 within frame extension 12, thence through the hollow shaft 14 in a direction opposite but in axial alignment with its previous travel through hollow shaft 16, thence 60 once around the grooved periphery of gripping roller 39 and then over the bending roller 38, where it is preferably again bent at an acute angle while receiving the second half twist between gripping roller 39 on the rotating bracket 22 and bending roller 38 on the stationary bracket shelf 37 (Fig. 3) imparting to the wire the ultimately desired pitch. Thence the now finally 65 twisted wire is fed through the remaining rollers mounted on shelf 37 and is finally wound up on

the tapered drum E or fed directly into a screw nail making machine.

Twisted wire receiving drum E revolving with vertical shaft 47 has a cylindrical narrow bottom section upon which the twisted wire 54 is continuously wound and a wide tapered top section upon which the coils of wire are continuously slipped. This type of tapered winding drum is old and well known in the wire making art.

Since the wire coming from the lower untwisted wire supply drum D is treated in exactly the same manner and passes through identical operations, a duplication of description is deemed unnecessary.

From the foregoing description of the machine and its operation it will be readily understood that during a single revolution of the frame A and its attachments, two axial half twists in the same direction are given the wire coming from wire supply drum C at two spaced points of the machine, the first half twist being imparted to the wire while it is travelling in the right hand direction of the machine, as viewed in Fig. 1, the second half twist being exerted upon the wire while it is travelling in the opposite direction. Also, that during the same revolution of the frame A the same treatment is given to a second wire coming from the lower wire supply drum D. The capacity of the machine is thereby greatly increased over similar machines heretofore used or disclosed. Also, that by this method and arrangement the speed of revolution of the frame A is cut in half and the wear and tear due to centrifugal action correspondingly decreased. Also, that only one frame A and attachments are required where duplicates were heretofore needed. Also that the wire supply drums or wire receiving drums need no longer be subjected to the disadvantages of bodily revolution and its attendant centrifugal wear and tear.

Instead of winding the twisted wire upon the drums E and F, these drums may be substituted by screw nail forming machines and the twisted wire may be fed directly in to such screw nail machines which cut the wire into desired lengths, form heads thereon and shape the other ends into sharp points.

It is to be understood that while I have illustrated and described the respective gripping means 34, and 39 as rollers, it is within the scope of my invention to provide any suitable substitute gripping means. Also, that while I have illustrated and described the rollers 38 and 38' as bending rollers, with curved wire engaging grooves to permit slipping of the wire while the latter is also being bent at an acute angle in accordance with the Jensen principle, these rollers may be mere gripping rollers or other suitable gripping means, the main principle being to grip the wire between two gripping means, a comparatively short distance apart, one revolving and the other being stationary.

It is also to be understood that while I have stated, as an example, that the product of the method and machine is adapted for the making of screw nails my invention may be adapted for a variety of other purposes.

It is thought that the invention and many of its attendant advantages will be understood from the foregoing description, and it will be apparent that various changes may be made in the form, construction and arrangement of the parts without departing from the spirit and scope of the invention or sacrificing all of its material

advantages, the form hereinbefore described being merely a preferred embodiment thereof.

I claim:

1. A machine for twisting wire, comprising in combination a revoluble frame, a stationary frame within said revoluble frame, a stationary frame without said revoluble frame for supporting said revoluble frame, means for rotating said revoluble frame and for feeding a wire longitudinally thereof first in one direction and then in the opposite direction, and means mounted on said frame for twisting the wire in the same pitch direction once at each direction of feed.

2. A machine for twisting wire, comprising in combination, a revoluble frame, a stationary frame within said revoluble frame, a stationary frame without said revoluble frame for supporting said revoluble frame, a wire supply reel mounted upon said first mentioned stationary frame from which a wire to be twisted is fed, means for rotating said first mentioned frame and for feeding said wire longitudinally thereof, first in one direction and then in the opposite direction, and means mounted on said frames for twisting the wire in the same pitch direction once at each direction of feed.

3. A machine for twisting wire, comprising a stationary support; a rotatable frame mounted on the support; a non-rotating frame mounted within the rotatable frame; wire gripping and guiding means mounted on said frames; means for rotating said rotatable frame; and means for feeding a wire from a wire gripping and guiding means on the non-rotating frame on a line coincidental with the axis of rotation of the rotatable frame to a wire gripping and guiding means on the rotatable frame, and for further feeding the same wire from a wire gripping and guiding means on the rotatable frame on a line coincidental with the axis of rotation of the rotatable frame, but in a direction opposite to that of the first feeding, to a wire gripping and guiding means on the stationary support, whereby said wire is caused to be axially twisted twice in the same pitch direction.

4. A machine for twisting wire, comprising a stationary support, a rotatable frame mounted on said support, a non-rotating support for a plurality of reels of wire arranged to be fed to said frame, means for rotating said frame and for feeding each of said wires over said frame, first in one direction and then in the opposite direction, and means including said frame for twisting one wire successively in one pitch direction once at each direction of feed and for twisting the other wire successively in the opposite pitch direction once at each direction of feed.

5. A machine for twisting wire, comprising a stationary support, a rotatable frame mounted on said support, a non-rotating support for a supply of wire arranged to be fed to said frame, means for rotating said frame and for feeding a wire over said frame, first in one direction and then in another direction, and means for gripping a portion of said wire while an adjacent portion is twisted in the same pitch direction once at each direction of feed by means of rotating with said frame.

6. Apparatus for progressively twisting two separate substantially endless wires, comprising gripping means and twisting means, including only one rotatable frame, for simultaneously and progressively twisting the wires independently of each other as they are fed to the rotating frame in opposite directions, and means for feed-

ing the wires to said frame in opposite directions.

7. Apparatus for progressively twisting two separate substantially endless wires, comprising only one rotatable frame, means for feeding the wires independently of each other to the rotating frame in opposite directions, and means partially mounted on said frame for simultaneously and progressively twisting both wires independently of each other to a uniform pitch as the wires are fed to the rotating frame in opposite directions.

8. Apparatus for progressively twisting two separate substantially endless wires, comprising in combination, a rotatable frame, fixedly supported means for gripping each of said wires as each is fed to said frame, and means rotating with said frame for twisting each of said wires

cooperatively with said gripping means, said gripping means and said rotating means including said frame cooperatively twisting both of said wires simultaneously and independently of each other to a uniform pitch as the wires are fed to the rotating frame in opposite directions.

9. Apparatus for progressively twisting wire comprising a rotatable frame, means for feeding the wire to the frame successively in a plurality of opposed directions, and means partially mounted on the rotatable frame at each different path of feed to the frame, for twisting the wire in the same pitch direction, once at each feed in a different direction, as the frame is rotated and the wire fed.

GUNNAR L. WHIST.
